UNITED STATES PATENT OFFICE.

FRANK COIC, OF ALEXANDRIA, VIRGINIA.

MACHINE FOR REMOVING SNOW.

Application filed November 15, 1926. Serial No. 148,504.

This invention relates to a machine for removing snow and has for its object the provision of a mobile device for taking up snow from a sidewalk or roadway and reducing the 5 snow to a liquid state without the application of heat for the purpose of such reduction.

These objects are attained by the mechanism hereinafter described, it being understood that changes may be made in the device 10 within the scope of the claims, without departing from the spirit of the invention or sacrificing any of the advantages thereof.

In the drawing:

Figure 1 is a plan view of the machine.

Figure 2 is a longitudinal sectional view.

Figure 3 is a section taken on line 3—3 of Figure 2.

Figure 4 is an end elevation of the machine.

Figure 5 is a sectional view taken on line 5—5 of Figure 3 and

Figure 6 is a view in elevation of a perforated disk forming a part of the device.

Referring to the drawing, the numeral 1 25 designates a frame provided with attaching ledges 2, whereby the device may be mounted on a wheeled vehicle or on a sled.

A cylindrical casing 3 is secured to the frame 1 and is closed at the rear end as shown 30 at 4, providing a saturating chamber. A plow or scoop 5 is secured at the forward end of the drum 3, and is inclined downwardly toward its front end to provide a cutting edge 6 which travels close to the surface of 35 the roadway.

A main shaft 7 is mounted in bearings 8 and 9 located at the front and rear ends respectively of the casing 3. Oil cups 10 are provided for lubrication of the shaft 7 in its 40 bearings. The bearing 8 is supported in the forward end of the casing by a spider 11 secured to the casing as shown at 12. A cutter 13 is mounted for rotation in the front of the casing, the cutter comprising a plurality of 45 adjustably mounted cutting or shaving blades 14, the active edges of which project through openings 15 in a disk 16 forming a part of said cutter. The disk is secured to the shaft 7 as at 17 and is provided with tapered enlargements 18 adjacent the openings 15 into 50 which bolts 19 are threaded for adjustably securing the blades to the disk.

The outer end of the shaft 7 is provided 55 with a cone-shaped member 20 which rotates with the shaft 7 above the scoop or plow 5,

whereby the mass of snow is divided and evenly distributed to the cutter.

A longitudinally extended counter shaft 21 is mounted in the frame directly beneath the shaft 7 and receives motion from the shaft 7 through the gears 22 and 23 secured to shafts 7 and 21 respectively.

A belting compartment 24 is formed beneath the casing 3 through which the shaft 21 extends. Mounted in the compartment 24 and secured on the shaft 21 for rotation therewith is a beating drum or roller 25 having a serrated outer surface as shown. The serrations may be of any desirable configuration best adapted to reduce snow brought 70 into contact therewith to a liquid state. Secured to the shaft 7 at the rear of the casing is an abrading member in the form of a perforated disk 26 adapted to rotate against the snow and slush in the casing and by frictional engagement with the same cause it to melt rapidly.

Tanks 27 are provided at either side of the chamber 24 and communicate therewith through a plurality of pipes 28. The lower 80 end of the pipes are located near the bottom of the compartment 24, the discharge end of the pipes enter the tanks 27 near the top thereof.

A pump 29 is located at the rear of the machine and is driven by chain and sprocket connections 30 from the shaft 21. The intake of the pump is connected to one of the tanks 27 as shown at 31 and discharges through the pipe line 32 to a header 33 located in the top of the casing 3. In the present 90 instance the header has been shown as a single pipe having a series of perforations for directing water at various angles to thereby saturate the entire contents of the chamber. The header however may comprise a plurality of pipes connected to accomplish the result desired. The tanks 27 are connected by pipes 34, so that water may pass from one to the other.

A relief cock 35 is provided at the top of the tank for permitting overflow therefrom when the tanks are filled. If desired a slatted conveyor 36 may be mounted on the scoop 5 as shown and driven by suitable gearing 37 connected to the shaft 21. Plugs 38 are 105 threaded in the bottom of the compartment 24 so that the water may be withdrawn and the compartment cleaned.

In operation of the device power is applied from any suitable source to the shaft 7 and 110

the machine is moved along the roadway under its own power or otherwise as desired. Snow is scooped up by the plow and moved toward the cutting head being assisted in 5 its ascent of the scoop by the conveyor. The distributor separates the mass of snow and delivers it to the cutting head. The cutters having been previously adjusted to take the requisite bite into the snow mass, adjustment 10 of the bite depending on the consistency of the snow. The snow enters the cylinder from the cutters and is saturated by water from the header as it passes to the rear of the cylinder to be acted on by the swiftly revolving abrading disk. The snow mass by this 15 time has been reduced to slush and falls on the beater, which it will be noted, is traveling at a high peripheral speed as compared to the speed of the cutting head and abrading disk. It will also be noted that rotation of 20 the beater is in an opposite direction to that of the cutters and disk mounted on the drive shaft so that an added frictional engagement is had with the snow as it is swirled by the 25 beater within the melting chamber.

When the chamber is filled with water to the level of the outlet end of the pipes 28, it flows into the tanks and is withdrawn therefrom by the pump to be reintroduced 30 to the interior of the casing through the header. Water is thereby circulated through the device to assist in melting the snow, the surplus escaping through the relief cock.

I claim:—

1. A machine for removing snow comprising a vehicle having a plow, a saturating chamber positioned to the rear of the plow and adapted to receive snow from said plow, a rotating member adapted to abrade the 40 snow in the chamber, means for saturating the snow in the chamber, a compartment for receiving the saturated snow, a beater within the compartment and extending within the chamber and adapted, when rotated, to throw water through the snow within the chamber, and means for transmitting water from the compartment to the means for saturating the 45 snow.

2. A machine for removing snow comprising a vehicle having a plow, a saturating chamber positioned to the rear of the plow and adapted to receive snow from said plow, a rotating member adapted to abrade the snow in the chamber, means for saturating the 50 snow in the chamber, a compartment for receiving the saturated snow, rotatable means within the compartment and extending within the chamber and adapted, when rotated, to throw water through the snow within the chamber, means for transmitting water from the compartment to the saturating means, and means rotatable within the chamber 55 above the first mentioned rotatable means to assist in breaking up the snow and melting 60 the same.

3. A machine for removing snow comprising a vehicle, a plow, a saturating chamber positioned to the rear of the plow and adapted to receive snow from said plow, a cutter positioned in the forward end of said chamber adapted to remove the snow from the plow and to deliver the snow to the chamber in small particles, means for saturating the snow in the chamber, rotatable means within the chamber for abrading the snow, a melting 75 compartment beneath the saturating compartment, a beater located in the melting compartment and adapted to throw water through the chamber to melt the snow, and means for transmitting water from the melting compartment to the saturating chamber. 80

4. A machine for removing snow comprising a vehicle, a plow, a saturating chamber positioned to the rear of the plow, a cutter, a rotatable member located in advance of the 85 cutter and adapted to divide the snow as it passes to the cutter, a saturating chamber for receiving snow from the cutter, a rotatable abrading member located in the chamber, a header in the chamber for directing water 90 against the snow in the chamber, a beater located below the abrading member and rotatable in an opposite direction thereto and at a speed greater than the abrading member, a melting compartment, and a pump for 95 spraying water from the compartment through the header into the chamber.

5. A machine for removing snow comprising a vehicle, a plow, a saturating chamber positioned to the rear of the plow, a rotatable 100 cutter in the forward end of the chamber, a member rotatable with the cutter for dividing the snow and directing it evenly to the cutter, a conveyor located in the plow for assisting the delivery of snow to the cutter, an abrading member rotatable with the cutter and located in the chamber to the rear of the cutter, a melting compartment beneath the chamber, a beater rotatable in the compartment 105 and extending into the chamber, and means for transmitting water from the compartment to the chamber for saturating the snow in the chamber. 110

6. A machine for removing snow comprising a vehicle, a plow, a saturating chamber 115 located to the rear of the plow, a cutter in the forward end of the chamber, an abrading member in the chamber, the cutter and abrading member being mounted for rotation, a melting chamber, a rotatable beater in the melting chamber, tanks located adjacent the melting chamber, means for maintaining a constant level of water in the chamber and tanks, means for simultaneously rotating the cutter and abrading member and the beater, the beater being rotated at a higher speed than the cutter. 120

In testimony that I claim the foregoing as my own, I have hereto affixed my signature.

FRANK COIC.
